E. H. HERSH

COAL TIPPLE ATTACHMENT

Filed Jan. 4, 1922

Edward H. Hersh
Inventor

N.E. Gee
By

Attorney

UNITED STATES PATENT OFFICE.

EDWARD H. HERSH, OF ALTOONA, PENNSYLVANIA.

COAL-TIPPLE ATTACHMENT.

Application filed January 4, 1922. Serial No. 526,381.

To all whom it may concern:

Be it known that EDWARD H. HERSH, a citizen of the United States, residing at Altoona, in the county of Blair and State of Pennsylvania, has invented certain new and useful Improvements in Coal-Tipple Attachments, of which the following is a specification.

This invention relates to an improvement 10 in attachments for coal tipples.

A primary object is an improved means whereby the flow of coal discharged from the tipple can readily be controlled such that motor trucks and cars can be more 15 easily loaded without the usual waste of coal.

Another object of this invention is to provide an improved means of opening the coal chute which permits the coal to flow uninterrupted into the trucks or cars by which it is to be transported, together with means for interrupting the flow of coal at the time said trucks or cars are loaded, thus avoiding 20 the usual waste incident to the loading operation.

A further object of this invention is to provide a convex disk to act as a coal cut-off device positioned between the coal tipple and the truck or car that is to be loaded, 30 said disk to be positioned in a bearing and provided with means for rotating the same in the journal bearings.

With these and other objects in view which will be more readily apparent as the 35 nature of the invention is better understood, the same consists in the novel construction, combination and arrangement of parts as will be hereinafter fully pointed out illustrated and claimed.

It will be readily understood by those skilled in the art to which this invention belongs that the same is susceptible of some structural changes and modifications without departing from the spirit or scope of 40 the invention but a preferred and practical embodiment of the invention is shown in the accompanying drawings in which:—

Figure 1 is a front elevation of my improved coal chute attachment as applied to 50 a coal tipple.

Figure 2 is a side elevation of the parts shown in Figure 1 of the drawings.

Figure 3 is a plan view of the parts shown in Figure 2 of the drawings.

Similar reference numerals refer to similar parts throughout the several figures of the drawings. 55

In carrying out this invention I provide the coal tipple T having the longitudinal beams or timbers 10, transverse beam 11, and upright posts or columns 12, with a novel closure device for controlling the delivery of coal. This device includes a rotary gate 13 in the form of a circular concavo-convex plate having an opening 14 cut on one side thereof for permitting the coal to pass. For the purpose of supporting this plate or disk I provide a shaft 13^a supported in bearings 15 and 16 carried by pendent arms 17 suspended from the cross beam 11 60 as shown in Figures 1 and 2 of the drawings. The axial portion of the plate adjacent the bearing 16 is provided with a combined ratchet wheel 18 and attaching disk 19, the latter being attached thereto by rivets 20 or the like. 65

The journal shaft 13 is preferably made in the form of a bolt having a circular head 21 adapted to coact with the face 22 of the bearing 15 while a nut 23 is provided at the 70 opposite end for keeping the parts in operative relation as shown in Figure 2 of the drawings. 75

For the purpose of rotating the disk 13 I provide in connection with the ratchet wheel 18 a pawl 24, fulcrumed on a lever 25 adapted to swing about the journal 13^a as a center as shown in Figure 1 of the drawings. The pawl 24 is provided with two engaging points 26 and 27, the pawl 26 being 80 engaged with the ratchet 18 when opening the coal chute and the pawl 27 engaging the same when the coal chute is closed. 85

After the coal passes through the opening 14 in the disk it enters a chute 29, from whence it is discharged into the truck or car arranged for its transportation to market. This chute can be attached in any desired way its only purpose being to direct the delivery of the coal after the same leaves the 90 tipple. 95

By reason of the fact that the concave side of the disk is arranged at the inside of the tipple the pressure of the coal will not bend or warp the same, but for the purpose 100 of the further assisting in relieving the disk of some of the bent pressure due to the weight of the coal against the same, the 105

edges of the disk may bear against the upright frame members 12 of the tipple as shown in Figure 1 of the drawings.

Without further description it is thought that the features and advantages of the present invention will be readily apparent and it will of course be understood that changes in the form, proportion and minor details of construction may be resorted to without departing from the spirit of the invention or scope of the appended claims.

I claim:—

1. In a coal tipple, a coal chute, means for cutting off the flow of coal from the tipple to the chute, including a disk of concavo-convex shape positioned between the tipple and the chute and having an opening adapted to register with the chute, means for rotating the concavo convex disk for cutting off the flow of coal from the tipple to the chute, and means for supporting the

disk comprising a journal and journal bearings together supported by the frame-work of the tipple.

2. A delivery gate for coal tipples including in combination with the framework of the tipple, and a discharge chute, a dished plate having an opening and journaled in the said framework, and means for rotating said dished plate to bring the opening into alignment with the discharge chute. 25 30

3. A delivery gate for coal tipples including in combination with the tipple framework and delivery chute, a dished disk having its concave side exposed to the pressure of coal within the tipple and also provided with an opening for aligning with the chute, and means for rotating the disk. 35

In testimony whereof he affixed his signature.

EDWARD H. HERSH.
